(57) CLAIM

The ornamental design for a eyebrow pen as shown and described.

DESCRIPTION

FIG. 1 is a perspective view of a eyebrow pen showing my new design, in a split state;

FIG. 2 is another perspective view thereof, in a split state;

FIG. 3 is a front view thereof, in a split state;

FIG. 4 is a back view thereof, in a split state;

FIG. 5 is a left view thereof, in a split state;

FIG. 6 is a right view thereof, in a split state;

FIG. 7 is a enlarged top plan view thereof, in a split state;

FIG. 8 is a enlarged bottom plan view thereof, in a split state;

FIG. 9 is a partial enlarged view of portion 9 in FIG. 1;

FIG. 10 is a partial enlarged view of portion 10 in FIG. 2; and,

FIG. 11 is another perspective view thereof, in merged state.

The broken lines depict portions of the eyebrow pen and form no part of the claimed design.

The dot dash line is included for the purpose of illustrating the bounds of the enlarged view and forms no part of the claimed design.
